G. FACCIOLE

INSULATOR

Filed Nov. 8, 1918

Inventor:
Giuseppe Faccioli,
by *Alfredo Dami*
His Attorney.

UNITED STATES PATENT OFFICE.

GIUSEPPE FACCIOLE, OF PITTSFIELD, MASSACHUSETTS, ASSIGNOR TO GENERAL ELECTRIC COMPANY, A CORPORATION OF NEW YORK.

INSULATOR.

Application filed November 8, 1918. Serial No. 261,597.

To all whom it may concern:

Be it known that I, GIUSEPPE FACCIOLE, a citizen of the United States, residing at Pittsfield, in the county of Berkshire, State of Massachusetts, have invented certain new and useful Improvements in Insulators, of which the following is a specification.

My invention relates to insulators for electrical conductors and particularly to insulators of the type known as bushings which provide for the insulation of a conductor more or less completely surrounded by another conductor at a materially different potential. An object of my invention is to reduce the size of insulators, particularly the length thereof. I accomplish the objects of my invention by modifying the electrostatic flux distribution in a desired manner so as to secure generally a more uniform distribution of the potential over the surface or surfaces of the insulating mass of the insulator.

In substantially all insulators there are two ways in which the insulator may fail: 1st, by breakdown through the insulating material; 2d, by creepage or arcing over the surface or surfaces of the insulating material. Quite generally the prevention of arcing or creepage over the insulating material determines to a material extent the size of the insulator, and particularly the length of the insulating mass. Generally, also, unless some means is provided to equalize the potential per unit of length, or gradient over the surface of the insulating mass, the potential will be distributed over the surface of the insulating mass in a very un-uniform manner, some portions of the surface of the insulating mass being subjected to materially higher potentials per unit length than other portions. It is of course necessary so to design the insulator, and make it of such size, and length in particular, that the average potential at no point on the insulator surface exceeds a certain safe value. Hence, when the potential is not uniformly distributed over a surface of the insulator, the insulator must be given a greater size than if the potential were distributed substantially uniformly.

In the practice of my invention, I provide means by which it is possible to equalize the potential per unit length over the insulating mass between the conductors, and to distribute the potential over the surface or sur-

faces of the insulating mass substantially uniformly. This means comprises a plurality of members of conducting material disposed adjacent the surface or surfaces of the insulating material and electrostatically related to both conductors so as to redirect the electrostatic flux, creating thereby the desired potentials at desired points on the insulating surface. These members may be a plurality of metallic petticoats of such sizes and so spaced and related to the conductors as to receive the desired potentials.

For a more complete understanding of the nature and objects of my invention reference should be had to the following detailed description, taken in connection with the accompanying drawing in which Fig. 1 shows an insulating bushing, partly in section, embodying my invention; while Fig. 2 shows a modified form.

Referring now to Fig. 1, 10 represents an electrical conductor, such as a lead for enclosed high tension electrical apparatus, and 11 represents an electrical conductor or structure at a materially different potential from the lead 10, which surrounds the lead 10, and frequently is and will here be supposed to be in conducting relation with the casing for enclosed electrical apparatus, from which casing the lead 10 is to be insulated.

12 denotes the upper insulating member comprising a portion of an insulating bushing which may be of molded porcelain, and 13 denotes the lower member.

The lead or conductor 10 is secured in a suitable manner in the insulating bushing, which may be solid or filled with an insulating medium, such as oil or insulating compound here indicated at 14.

In the further description of the bushing shown in the drawing, I will describe my invention as applied only to the upper insulating member 12 because the lower member is usually submerged in oil although obviously my invention is equally applicable to the lower member when it is not so submerged, as for instance, when it passes through the wall or roof of a building.

To alter the potential at one or more points on the surface of the insulating member 12, I place thereon one or more conducting annular members or rings such as are shown at 15, 16, 17, 18, 19 and 20. These

members are preferably secured beneath the surface of the insulating member 12 as shown, and are so shaped that they do not coincide with any of the natural system of 6 equipotential surfaces drawn for the unmodified potential distribution, such as are indicated by S and S', and shown as intersecting the insulating surface at points a and b where certain of the annular conduct- 10 ing members are applied.

By suitably shaping such conducting members and disposing them with respect to the conductors themselves I alter the electrostatic flux and, consequently, the distribution 15 of potential along the surface of the insulating member 12 between the conductors 10 and 11. By properly selecting the size, deflection and distribution of these conducting annular members, I am enabled to secure 20 a desired distribution of potential over the surface of the bushing as will be more readily understood from the following consideration.

Suppose now that no conducting members 25 have been provided along the surface of the insulating member 12 between the conductors 10 and 11 and that there is a potential difference of 100,000 volts between conductors 10 and 11, the conductor 11 being at 30 ground potential, and that the potential difference from conductor 11 to point a is 60,000 volts, and further suppose that the point a is half way along the distance over the surface of member 12, between the conductors 10 and 11. It may be imagined that 35 the capacity between the conductors 10 and 11 is composed of two capacities in series; that is, the capacity between the conductor 10 and the point a and the capacity between 40 the point a and the conductor 11. Then, in accordance with the well known law of electrostatics, the potentials on each side of point a are in inverse proportion to the capacities on each side thereof, i. e., inversely 45 proportional to the capacities naturally on the respective sides of the unmodified equipotential surface S passing through point a. Consequently, if V_1 denotes the potential 50 from conductor 10 to point a and C_1 the corresponding capacity, and if V_2 denotes the potential from point a to conductor 11, and C_2 the corresponding capacity, we would have

$$\frac{V_1}{V_2} = \frac{C_2}{C_1} = \frac{40,000}{60,000}$$

which shows, according to the above supposition, that the natural capacity between the surface S and the conductor 10 is one 60 and a half times greater than that between the surface S and the conductor 11. Then, to proportion relatively the potential distribution on the two sides of point a, it is necessary to increase the last referred to capacity, or that denoted C_2 in the above for-

mula, by an amount substantially one-half its original value in order to be equal to that on the other side of surface S. Obviously, this can be done by connecting a condenser having this required capacity from point a 70 to the conducting structure 11, (that is, in parallel with the natural capacity C_2); but as above noted this increase in capacity is preferably to be accomplished by suitably shaping and disposing the annular conduct- 75 ing member secured at a, here denoted as member 17.

It is to be observed that if member 17 was so shaped that its surface coincided with the surface S, there would be no alteration of 80 the electrostatic line of force traversing the surface S and consequently no change in the capacity or potential distribution on the two sides of point a. If though, the surface of member 17 is bent downwardly away from 85 the natural equipotential surface S, as shown, a greater effective surface of the member 17 is presented to the conducting structure 11 so that the capacity from surface S to this structure is thereby increased 90 in an amount depending on the bending; the angle through which it is deflected or bent being determined by the capacity it is desired to add.

By a repetition of this process of bending 95 the conducting members intermediate point a and the conductors 10 and 11, through determinable angles out of the natural equipotential surfaces intersecting the insulating surface at the points where they are applied, the capacities between each point lying 100 along a line in an axial plane of the insulator, may be as nearly proportionately distributed as may be desired, consequently the average potential over the insulating surface will have been approximately equalized for all points in this manner.

The function of the conducting annular members 15 to 20 may be explained in another manner. Assuming as before that without these members, the potential at the point a is 60,000 when there is a potential difference of 100,000 between the conductors 10 and 11. A potential of 50,000 is desired at the point a as this point is half way between the conductors 10 and 11. The annular member 17 is applied at the point a and deflected as shown away from the natural equipotential surface S and into a region of naturally lower potential. Being of conducting material, the entire annular member 17 will assume the same potential and this will be the average of the natural electrostatic field through which this member 17 extends. The deflection and the extent of the member 17 is therefore so determined that it must assume the desired potential of 50,000. Other points along the surface of the insulating member 12 are brought to desired potentials in similar manner by apply-

ing at such points other conducting annular members of suitable extent and deflection.

The conducting rings distributed over the insulating surface may in some instances be designed to serve not only as a means for equalizing the potential distribution over such surface but also as a petticoat structure. This use of conducting rings secured to the surface of the insulating member has been illustrated in Fig. 2. Here the rings 15' to 21' are given a downwardly sloping direction which permits rain and falling particles to freely glide off the insulating structure.

Having now described what is at present the best means known to me for carrying out an embodiment of my invention, I would have it understood that such means are merely illustrative and that I do not mean to be limited thereby to the exact details shown nor in the choice of recognized equivalents except as defined in my claims hereunto appended.

What I believe as new and desire to secure by Letters Patent of the United States, is:—

1. The combination with two adjacent conductors, of a mass of insulating material therebetween to insulate each from the other, and a plurality of conducting members extending outwardly from an outer surface of said insulating material between the two conductors, said conducting members being extended and deflected to dis-

tribute a potential difference between said conductors substantially uniformly along 35 said surface.

2. The combination with a conductor, of an annular conductor surrounding the same intermediate its length, insulating material between said conductors for insulating each 40 from the other, and a plurality of conical rings of conducting material surrounding said first named conductor and extending outwardly from a surface of said insulating material between said conductors, said rings 45 being extended and deflected to distribute a potential difference between said conductors substantially uniformly along said surface.

3. The combination with a substantially 50 linear conductor, of a conducting structure surrounding the same intermediate its length, insulating members secured between said conductor and each side of the structure thereby forming a bushing, and a plurality 55 of conical rings of conducting material extending outwardly from the surface of the bushing at predetermined points, said rings being extended and deflected to distribute a potential difference between said conductor 60 and conducting structure substantially uniformly along said surface.

In witness whereof, I have hereunto set my hand this second day of November, 1918.

GIUSEPPE FACCIOLE.
